JOSEPH H. WILKINSON, OF CONCORD, NEW HAMPSHIRE.

Letters Patent No. 101,955, dated April 12, 1870.

IMPROVEMENT IN WOOD PAVEMENTS.

The Schedule referred to in these Letters Patent and making part of the same.

To all whom it may concern:

Be it known that I, JOSEPH H. WILKINSON, of Concord, in the county of Merrimac and State of New Hampshire, have invented a new and useful Improvement in Wood Pavements for Horse-Railways and Street-Crossings; and I do hereby declare the following to be a full, clear, and exact description of my invention, its construction and operation, reference being had to the accompanying drawings making part of this specification, in which—

Figure 1 is a perspective view;

Figure 2, a longitudinal view; and

Figure 3, a transverse section.

Before describing my improvement, it may be well to state how horse-railway tracks are constructed to the end that those skilled in mechanics may understand the adaptation of my pavement to the same.

In the construction of horse-railway tracks the earth is usually removed to the depth of about ten inches. Trenches are then made, into which sleepers, A, similar to those used in steam-railroad beds are laid. These sleepers are very firmly bedded.

On the sleepers parallel rail-beds, B, are placed. These are usually about seven inches deep and five wide.

On these rail-beds the rail-track c is made secure.

The sleepers being firmly bedded in the ground, a very solid foundation is secured for any substructure resting upon them.

In laying my pavement between a horse-railroad track, I first remove the earth to the level of the sleepers. I then take, say, four planks, two inches thick, and mold the inner faces of the two outside planks, as shown at D D, the two inside planks being molded as shown at E E. These four planks I rest on their edges on the sleepers A, and the earth between the sleepers, or whatever other substance may be laid on the earth.

The planks are now in the form of keys. Between the keys E and E I place blocks of wood, say, ten inches wide and four or five inches thick, this thickness being immaterial.

The blocks of wood are formed as represented at F F. It will be observed that the blocks are so constructed as to furnish recesses for the projections on the keys. These projections form a shoulder for the blocks to rest upon.

This arrangement, the strength of the key being duly considered, plainly shows that the blocks cannot sink, while the dovetail form of the lower half of the blocks prevents them from rising, thereby giving vastly greater solidity and strength to the whole structure,

and also preserving a much more even surface than by any method before devised.

I would call especial attention to the form and arrangement of the key-planks, as, owing to their depth with respect to their blocks, and the shoulder formed upon them, they form an unusually strong and powerful means of sustaining the thrust and concussion upon the blocks.

In manufacturing my pavement, it can be made of any desired length and width for laying down in sections, and which, while each section would be formed of many blocks and continuous keys, yet each section becomes an integral whole.

It will further be observed that the blocks are provided with a V-shaped groove in the upper half, and spaces left between the blocks and keys in the lower half. This arrangement is to allow of expansion consequent upon rains, &c. I design filling the grooves with gravel and other material that will not set hard, except upon the surface, so that when the expansion takes place, the filling will yield. The grooves also serve as a preventive to horses slipping. When a horse loses his footing, he always places his foot outward diagonally with the length of the street, and seeks a bracing position. In this case the disposition of grooves aids him very much.

While my improvement requires that each set of blocks between each two keys shall be of the same width, (my keys being continuous,) it is not requisite that they be of the same thickness, but may be varied in thickness, as an economical working of the wood might render necessary or expedient.

It will be observed that the section does not quite fill the space between the railway-beds. The space left is for the facility of laying down and for reception of the same material that goes between the V-shaped grooves and other spaces, thus making another provision for expansion.

I do not claim having invented a wood pavement formed of blocks of wood and keys to hold the same; but

What I do claim, is—

The series of longitudinal keys, each formed with a tongue extending to, or nearly to, the surface of the blocks, shoulders to support the blocks and tapering from the shoulders to the base, in combination with blocks formed to fit said keys, as herein described, the keys being supported upon the sleepers or other substructure, as set forth.

Witnesses: JOSEPH H. WILKINSON.
